UNITED STATES PATENT OFFICE.

ROY W. SEXTON, OF WYTHEVILLE, VIRGINIA.

BRIDGING EXPANSIBLE FILLER FORM.

Application filed October 28, 1916, Serial No. 128,305. Renewed March 26, 1921. Serial No. 455,981.

To all whom it may concern:

Be it known that I, Roy W. Sexton, a citizen of the United States, and a resident of Wytheville, county of Wythe, and State 5 of Virginia, have invented certain new and useful Improvements in Bridging Expansible Filler Forms, set forth in the following specification.

This invention relates to washable expandable 10 filler forms for hand-embroidery, such as serve both as a pattern for the embroidery work and as a filler to raise the embroidery threads from the general level of the textile fabric embroidered.

Expansible filler forms of this character 15 have been made from felted cotton and woolen fiber compressed and held under compression by an incorporated water soluble binding agent so that the form would be sufficiently stiff and shape-retaining to 20 serve as a satisfactory pattern form to guide the application of embroidery threads. It has been found, however, that only the skilled embroidery expert is capable of applying 25 embroidery threads over any kind of embroidery filler so that each thread will have the same tension as that of its neighbor. It has also been found that when a piece of embroidered fabric, with an expansible 30 filler form incorporated under the embroidery threads, is laundered or otherwise treated to remove the water soluble binder and permit the expansion of the filler form, the consequent expansion of the 35 filler form expands the overlying embroidery threads to relatively unequal amounts in a degree inversely proportional to the tension in the different embroidery threads. This results in an irregular, inartistic appearance 40 of the finished embroidery.

Filler forms for embroidery are intended 45 for use by amateurs and novices in the art of embroidery as well as experts. It is therefore of decided advantage to insure as even an appearance to finished embroidery 50 as can be accomplished. When a non-expansible embroidery form is employed the inequalities in the tension of the embroidery threads have little effect upon the appearance of the finished embroidery within reasonable limits, but an expansible embroidery form has the advantage over the non-expansible form of imparting to the finished embroidery a desirable rounded appearance

from the central portion of an embroidered 55 part down to the edges of said embroidered part.

An object of the present invention is to make possible the employment of the rounded effect imparted by an expansible 60 embroidery filler form and to eliminate the disadvantage of inequalities in the finished embroidery due to unequal thread tension. To this end I have discovered that the provision of a bridge incorporated on and, to 65 a limited extent, below the thread engaging surface or top surface of an expansible embroidery form serves the purpose of equalizing the expansion of the filler form from thread to thread and prevents the bunching 70 or inequalities.

The above and the general object of my invention, to improve filler forms for embroidery, will be clear from the following detailed specification and are pointed out 75 in the following claims which may be understood by reference to the illustrative embodiments described in the specification and shown in the accompanying drawings which form a part hereof, and in which like characters designate corresponding parts in the several figures. In the drawings Fig. 1 is a perspective view illustrating the manner in which the expansible filler forms are employed; Fig. 2 is a fragmentary section 80 drawn to an enlarged scale through line II-II of Fig. 1, illustrating an expansible filler form immediately after the embroidery has been applied; Fig. 3 is a view of the same structure drawn to the same 85 scale as that shown in Fig. 2, after the binder in the filler form has been removed and the filler form has been permitted to expand; Fig. 4 is a fragmentary sectional view taken along line IV-IV of Fig. 2; Fig. 5 is a view similar to Fig. 4 but taken 90 along line V-V of Fig. 3; Fig. 6 is a greatly enlarged fragmentary section of a filler form embodying my invention; Fig. 7 is a fragmentary section taken in the locality of the line II-II of Fig. 1 through a piece of embroidery work embodying a 95 filler form of my invention and after the removable binder has been removed to permit the expansion of the filler form; and Fig. 8 is a section through line VIII-VIII 100 of Fig. 7.

In practicing my invention I prefer to

employ felt of the desired thickness made up of a mixture of about 80% cotton fiber and about 20% animal fiber such as wool, although I may employ cotton-felt or wool-
5 felt, or combined cotton and wool-felt, in other proportions than 20% to 80%. This felt fabric is first saturated and completely impregnated throughout all its fibers in a suitable manner as by immersion or by
10 passage between saturating rollers with a water solution of a suitable stiffening agent. I have found that a light-colored, starchy paste of the type commercially on the market for the purpose of applying labels is sat-
15 isfactory. I have also found that a solution of ordinary starch, preferably heat treated in the usual manner is satisfactory. I have also found that flour paste and albu-
20 men and sizing and even a saponaceous solu-
25 tion give satisfactory results. After the fabric sheet is thoroughly impregnated, it is dried and compressed so that its thickness after complete treatment is less than ordinarily in the unimpregnated felt. The
30 drying and pressing may be simultaneous, as between combined drying and pressing rollers. I have constructed embroidery forms from the stock which has merely been pressed and dried after saturation with a
35 removable binder as above, which held together in a relatively thin sheet by the binder which has been dried or hardened throughout the fibers of the stock. Such a
40 filler form is illustrated in Figs. 1, 2, 3, 4 and 5. Figs. 1, 2 and 4 illustrate such a form made of felt, pressed and filled with a binder removable by laundering, but before the laundering, of the entire embroidery article A comprising the textile
45 fabric 1, the filler form 2 and the embroidery threads 3. I have found that the average embroiderer does not give equal tension to the individual threads 3, so that after the piece of embroidery has been laun-
50 dered, the filler form 2 expands, as shown in Figs. 3 and 5, but it does not expand the same amount under all the embroidery threads. For example, of the threads 3 cer-
55 tain threads *a* have a greater tension than certain other threads *b*. The threads *a*, which have the most tension, locally prevent the complete expansion of the filler form 2, while the threads *b* permit the filler form to push up to form ridges or inequalities.
60 The illustration of Fig. 3 is, of course, slightly exaggerated for the careful embroidery, but some examples are actually as bad as the illustration. Fig. 5 shows particu-
65 larly well how the thread *b* is pushed up farther than the thread *a*, although the contour of the thread *b* is well rounded in the cross-section of Fig. 5, as well as the contour of the thread *a*. I have found that, if I form a bridge 4 on, in and, to a slight extent, below the thread engaging surface 5 of the stock 6 which has previously been impregnated and compressed as I have de-
70 scribed above, so that it contains throughout its section a binder removable by laun-
75 dering, the inequalities in the finished em-
broidery are completely eliminated and yet the desirable expansibility is maintained. This bridge I may form by applying a light impregnating surface filling of a wa-
80 ter insoluble binder such, for example, as acetyl-cellulose dissolved in chloroform or nitro-benzole, or a water and heat resisting
85 gelatine formed by treating gelatine with formaldehyde as described in United States Letters Patent to Hauser, 572,295, granted Dec. 1, 1896, or I may employ with a high degree of satisfaction a surface impregna-
90 tion 4 of a mixture of bees-wax and pow-
dered talc or powdered soapstone, or of bees-wax alone. This surface impregna-
95 tion may be applied by means of a heated roller carrying a surface film of the bees-
wax mixture. The pulverulent material added to the bees-wax is not absolutely nec-
essary but tends to make the bees-wax coat-
99 ing permanent and to build and smooth over any inequalities in the thread engaging surface 5 of the filler form. I have found that such a bees-wax surface impregnation is substantially irremovable by laundering and that it forms a satisfactory bridge from thread to thread of the overlying em-
100 broidery threads so that, when the piece of embroidery B has been laundered as shown in Fig. 7, the embroidery threads 3 are all pushed out to a substantially uniform ex-
tent, and if certain of the threads are not as tight as others, the bridge 4, by bridging across from one tight thread to another tight thread, satisfactorily holds down the body 6 of the embroidery form so that the surface of the embroidery has a uniform ap-
105pearance. The cross-sectional view shown in Fig. 8 shows how none of the threads 3 project out from the fabric 1 farther than another, while a satisfactory rounded ap-
110pearance to the finished embroidery is im-
parted. The bridge 4 thus constitutes a layer of tough, tenacious, substantially in-
115extensible material fixed to the body of felt-
ed fibers beneath it and serving to prevent bunching and distortion of said body. The term "non-removable" as used in the claims with respect to a "binding agent" or "binder" means a binder or agent that is not removable by washing or laundering in water, or in solutions of water and soap, or similar cleansing agents, such as commonly used in laundering fabrics. The term "re-
120moveable" as used in the claims with respect to a "binder" means the converse of "non-removable". The term "soluble" as em-
ployed in the claims with respect to a "binding agent" or a "stiffening agent", means one that is soluble in water, or in solutions
125
130

of water and soap, or similar cleansing agents, such as commonly used in laundering embroidered fabrics.

What I claim and what I desire to secure
5 by United States Letters Patent is:

1. A filler form for embroidery, consisting of an expansible fabric and an incorporated removable binding agent by which the fabric is stiffened and held under compression, and a substantially non-removable binder incorporated on and to a limited depth below its embroidery thread engaging surface to form an expansion equalizing bridge from thread to thread of the embroidery.

2. A filler form for embroidery, consisting of an expansible fabric and an incorporated removable binding agent by which the fabric is stiffened and held under compression, and a substantially non-removable bridge incorporated across the embroidery thread engaging surface to form an expansion equalizing bridge from thread to thread of the embroidery.

25 3. A filler form for embroidery, consisting of an expansible, fibrous material and an incorporated starch binder by which the fibrous material is held under transverse compression, and a substantially non-removable binder incorporated on and to a limited depth below its embroidery thread engaging surface to form an expansion equalizing bridge from thread to thread of the embroidery.

35 4. A filler form for embroidery, consisting of an expansible fibrous material and an incorporated soluble binding agent by which the fibrous material is held under transverse compression, and a substantially non-removable binder incorporated on and to a limited depth below its embroidery thread engaging surface to form an expansion equalizing bridge from thread to thread of the embroidery.

45 5. A filler form for embroidery, consisting of an inherently expansible and elastic fibrous material with the fibres matted together and an incorporated soluble binding agent by which the material is stiffened and held under transverse compression, said binding agent being removable by washing to permit the form to expand, and a substantially non-removable binder incorporated on and to a limited depth below its embroidery thread engaging surface to form an expansion equalizing bridge from thread to thread of the embroidery.

60 6. A filler form for embroidery, having a thread-engaging surface and comprising a body of normally flexible expansible fabric compressed beyond its normal density and saturated by a water soluble stiffening agent maintaining it in compressed condition, said fabric being capable of expansion to its normal dimensions and resuming its normal

flexibility and fullness when said stiffening agent is washed out, and a substantially non-removable binder incorporated in and to a limited depth below its embroidery thread engaging surface to form an expansion equalizing bridge from thread to thread of the embroidery.

70 7. A filler form for embroidery, having a thread-engaging surface and comprising a body of felt compressed beyond its normal density and saturated by a water soluble stiffening agent maintaining it in compressed condition, whereby said body is adapted to expand to its normal dimensions when said stiffening agent is washed out, and a substantially non-removable binder incorporated in and to a limited depth below its embroidery thread engaging surface to form an expansion equalizing bridge from thread to thread of the embroidery.

75 8. A filler form embodying an embroidery design comprising a body of flexible expansible fabric compressed beyond the normal density and saturated by a water soluble stiffening agent maintaining it in compressed condition, said fabric being capable of expansion to its normal dimensions and resuming its normal flexibility when said stiffening agent is washed out, and a substantially non-removable binder incorporated on and to a limited depth below its embroidery thread engaging surface to form an expansion equalizing bridge from thread to thread of the embroidery.

85 9. As a new article of manufacture, a filler form embodying an embroidery design comprising a body of compressed felt impregnated with a soluble stiffening agent, and a substantially non-removable binder incorporated on and to a limited depth below its embroidery thread engaging surface to form an expansion equalizing bridge from thread to thread of the embroidery.

90 10. A filler form embodying an embroidery design comprising a body of normally flexible expansible and compressible fabric compressed beyond its normal density, and stiffened by means of a stiffening agent, said fabric being held in compressed condition by said stiffening agent and being capable of expansion when brought into contact with a cleansing fluid and resuming its normal thickness and flexibility, and a substantially non-removable binder incorporated on and to a limited depth below its embroidery thread engaging surface to form an expansion equalizing bridge from thread to thread of the embroidery.

105 11. A washable filler form embodying an embroidery design adapted to be completely covered by embroidery threads and comprising a flexible form body of unwoven fiber uniformly felted together, a removable toughening binder impregnating said form body and solidified through the fibers of the

said form body from which it may be removed by washing in water, and a substantially non-removable binder incorporated on and to a limited depth below its embroidery 5 thread engaging surface to form an expansion equalizing bridge from thread to thread of the embroidery.

12. A filler form for embroidery, consisting of a body of fibrous material having 10 the embroidery thread engaging surface thereof incorporated with a substantially non-removable binder.

13. A washable filler form embodying an embroidery design adapted to be completely

covered by embroidery threads and comprising a flexible body of water-absorbent felted fibers having a layer of tough, tenacious, substantially inextensible material fixed to said body and serving to prevent bunching and distortion of said body, said layer being formed by impregnating a part of said body 15 of fibers at its thread engaging surface with a substantially non-removable binder.

In witness whereof I have signed my name to this specification, this — day of October, 1916.

ROY W. SEXTON.
